Morrisville, Pa.

Filed June 15, 1959, Ser. No. 820,522

1 Claim. (Cl. 41—11)

This invention relates generally to ornamental devices, and more particularly to an ornamental configuration which may be readily assembled to form a rigid three-dimensional object and which may be readily collapsed to a more compact form while remaining in an assembled condition.

Although numerous ornamental devices constructed of an assembly of fitted together notched and relatively thin sheets of material cut to conform to the profile of the article which the ornament is to represent have been heretofore proposed, these prior art devices have not been intrinsically capable of assuming a rigid three-dimensional configuration, or of assuming a substantially two-dimensional configuration while remaining in an assembled condition. In some of the prior art ornamental devices a separate spacing member is required for locking the assembled elemental sheets into the desired angularly displaced condition, while the majority of these presently available ornamental devices have to be completely disassembled for purpose of storage, packaging, or shipment.

Accordingly, it is a principal feature of this invention to provide a plurality of elemental means which may be securely assembled together to represent a three-dimensional configuration.

Another object of the present invention is to provide a three-dimensional assembly of elemental members which may be collapsed to assume a more compact form while remaining in an assembled condition.

Still another object of this invention is the provision of notched elemental members capable of being securely interconnected in a manner to assume a rigid assembly of members in three intersecting planes.

A further object of this invention is to provide a new and improved ornamental article of manufacture which may be made in a wide variety of designs, sizes and colors.

A still further object of the instant invention is to provide a plurality of notched sheets adapted to being interlocked in an assembly of three intersecting perpendicular planes, which assembly may be collapsed into a substantially single plane of sheets.

Other objects and many of the attendant advantages of this invention will be more readily appreciated as the same becomes better understood by reference to the following detailed description when considered in connection with the accompanying drawing wherein:

Fig. 1 is an elevational view of the ornamental object of the present invention in an assembled three-dimensional condition;

Figs. 2, 3, and 4 are elevational views of the individual elemental sheets making up the ornamental object of Fig. 1; and

Fig. 5 is an elevational view of the ornamental object of Fig. 1 in a collapsed condition.

Referring now to the drawing wherein like reference numerals designate identical or corresponding parts throughout the several views, and more particularly to

2

Fig. 1 whereon a three-dimensional ornamental object 10 having the profile of a six pointed star is illustrated. It will be clear that although the object 10 is illustrated as representing a star-like configuration, this is only by way of example and not limitation, and the object 10 may also be made to represent other configurations, such for example as a snow crystal. The three-dimensional article 10 is made up of three flat sheets 11, 12, and 13, each of which sheets is composed of a relatively thin and slightly flexible material, such for example as cardboard, or the like. The elemental sheets 11, 12, and 13 are shown in greater detail in Figs. 2, 3, and 4, respectively, of the drawing.

As more clearly shown in Figs. 2 and 3, the elemental sheets 11 and 12 are identical in profile and in construction, both sheets having a T-slit, 15a and 15b, respectively, formed therein. For the purpose of the instant star-like embodiment, the profile of sheets 11 and 12 are composed of six equidistantly positioned radially extending triangular shaped segments 16a and 16b, respectively, formed integral with a circular center segment, or portion, 17a and 17b, respectively. The center segments of both elemental sheets 11 and 12 are of identical size. The T-slits 15a and 15b consist of a base leg 18a and 18b, respectively, and a top leg 19a and 19b, respectively, perpendicular to its respective base leg. Since both T-slits are identically formed in their respective sheets, the manner of their construction and positioning will be described only with reference to the T-slit 15a of sheet 11. As shown on Fig. 2, the base leg 18a of T-slit 15a extends from the point of intersection of two adjacent triangular shaped segments 16a on the periphery of the central segment 17a, which point of intersection is designated by reference numeral 21, to the center 22 of the sheet 11, while the top leg 19a thereof consists of two equal length segments 25a and 26a. In other words, the base leg 18a is equal in length to the radius of the central segment, while the top leg 19a is equal in length to one-half the radius. For configurations other than the instant starlike object, the point 21 may be considered to be that point on the circumference of segment 17a midway between the points of intersection of a radial line drawn through the center of two adjacent radially extending segments with the circumference.

As more clearly shown in Fig. 4, the elemental sheet 13 also consists of a center circular segment, or portion, 17c, which is of the same size as the center segments 17a and 17b, and four equidistantly positioned radially extending triangular shaped segments 16c integrally formed therewith. The number of radial segments formed on sheet 13 is two less than the number formed on the other two elemental sheets. Extending radially inward of the center segment 17c from the points of intersection of each adjacent triangular segments with the periphery of the center segment are four radial slits 24a, 24b, 24c, and 24d, each of which is equal in length to one-half the length of top leg 19a of T-slit 15a. For other configurations, these slits extend from points on the circumference of the center segment which are midway between the points of intersection with the circumference of a radial line drawn through the centers of adjacent extending segments.

The width of each slit is preferably made equivalent to the thickness of the material of which the elemental sheets are fabricated to render the assembly more securely locked in a three-dimensional configuration.

In order to accomplish the three-dimensional configuration of Fig. 1, the following assembly procedure may be followed. First, slide slit 25a of sheet 11 into slit 24a of sheet 13. Next, slide slit 24c of sheet 13 inwardly through slit 18a of sheet 11 until slit 24c seats in slit 26a of sheet 11. The elemental sheets 11 and 13 will now

assume a perpendicular relationship relative to each other. Now hold sheet 11 with slit 18a in a vertically upright position and slit 24b of sheet 13 to face the observer. Insert slit 26b of sheet 12 into slit 24b of sheet 13. Then slide slit 18b of sheet 12 through slit 18a of sheet 11 and insert slit 25b of sheet 12 in slit 24d of sheet 13. With but minor manual adjustment of the relative spatial displacement of the elemental sheets, a rigidly and securely assembly of elemental sheets in three intersecting perpendicular planes, such for example as the six pointed star-like configuration of Fig. 1, will be obtained.

In order to collapse the three-dimensional configuration into a more compact form, the following procedure may be followed. Position sheet 12 in a horizontal plane with the slit 18b thereof to the left of the observer and sheet 13 in a vertical plane with the edge thereof toward the observer. With the right hand grasp the two triangular extensions of sheet 12 which are diametrically opposite the triangular extensions adjacent slit 18b, and with the left hand grasp the two triangular extensions of sheet 11 which are diametrically opposite the triangular extensions adjacent slit 18a. Then with the right hand twist the portion of sheet 12 nearest the observer downward and to the left, and simultaneously with the left hand twist the portion of sheet 11 below sheet 12 downward and to the right. If this specific collapsing procedure is followed, all of the elemental sheets will lie in a single plane in the relative positions shown in Fig. 5 of the drawing.

Obviously numerous variations and modifications of the instant invention are possible in the light of the above teachings. Accordingly, it is to be understood that within the scope of the appended claim the invention may be practiced otherwise than as specifically described herein.

What is claimed as new and desired to be secured by Letters Patent of the United States is:

An ornamental object comprising a trio of sheets of cardboard, each of said sheets having a center circular portion and a plurality of equiangularly spaced radially

extending portions integrally formed around the circumference of said center portion, said center circular portion of each of said sheets being of equal diameter, the number of radially extending portions of two of said sheets being equal and the number of radially extending portions of the third of said sheets being two less than the number of radially extending portions on said two sheets; and a plurality of slits formed in the center portion of each of said sheets by means of which said sheets 10 can be interlocked in an assembly of three intersecting perpendicular planes, and alternatively, collapsed into an assembly of a substantially single plane, the slits formed in said two sheets being of an identical T-configuration, the base leg of which extends radially inward from a point on the circumference of said center portion midway between two adjacent radially extending portions, the slits formed in the center portion of said third sheet 15 consisting of two pairs of diametrically opposed slits extending radially inward for a distance equal to one-fourth the diameter of said center portion, each of the slits formed in each of said sheets having a width equal to the thickness of said material.
